TREADMILL

Jordan D. Frasier, Orange, Calif., assignor to International Rectifier Corporation, Los Angeles, Calif., a corporation of California

Filed Apr. 21, 1969, Ser. No. 16,822

Term of patent 7 years

Int. Cl. D21—03

U.S. Cl. D34—5

FIG. 3

FIG. 5

FIG. 4

FIG. 6

FIG. 1 is an isometric view of the treadmill in an open position showing my new design; and

FIG. 2 is a left side elevational view thereof; and

FIG. 3 is a top plan view thereof; and

FIG. 4 is a front elevational view thereof; and

FIG. 5 is a top plan view in closed position; and

FIG. 6 is a front elevational view in closed position.

I claim:

The ornamental design for a treadmill, substantially as shown.
